UNITED STATES PATENT OFFICE.

ALVAH L. BENEDICT, OF SCHUYLERVILLE, NEW YORK.

SAFETY ATTACHMENT FOR BREASTPINS, &c.

SPECIFICATION forming part of Letters Patent No. 783,922, dated February 28, 1905.

Application filed November 23, 1904. Serial No. 234,089.

To all whom it may concern:

Be it known that I, ALVAH L. BENEDICT, a citizen of the United States, residing at Schuylerville, in the county of Saratoga and State 5 of New York, have invented a new and useful Safety Attachment for Breastpins and the Like, of which the following is a specification.

This invention relates to safety attachments for breastpins and the like.

10 The object of the invention is to provide a cheap, readily-applied, and simply-constructed form of attachment which by coaction with the ordinary catch or keeper in common use will positively prevent a pin from coming 15 unfastened; furthermore, to limit the movement of the pin relatively to the plate or object with which it is combined, thereby still further reducing the liability of unfastening of the pin.

20 With the above and other objects in view, as will appear as the nature of the invention is better understood, the same consists in the novel construction and combination of parts of a safety attachment for breastpins and the 25 like, as will be hereinafter fully described and claimed.

In the accompanying drawings, forming a part of this specification, and in which like characters of reference indicate corresponding 30 parts, there are illustrated three forms of embodiment of the invention, each capable of carrying the same into practical operation, it being understood that the elements therein exhibited may be varied or changed as to shape, 35 proportion, and exact manner of assemblage without departing from the spirit thereof, and in these drawings—

Figure 1 is a view in perspective exhibiting a breastpin having combined therewith the 40 attachment of the present invention, the pin being shown in locked position. Fig. 2 is a similar view, exhibiting the pin unlocked and the attachment in inoperative position. Fig. 3 is a view in side elevation of Fig. 1. Figs. 45 4 and 5 are perspective detail views of modified forms of the device.

Referring to the drawings, 1 designates the body of an ordinary breastpin, brooch, or the like, 2 the pin, and 3 the ordinary catch or 50 keeper commonly employed. As these parts

may be of the usual or any preferred construction, further description thereof is deemed unnecessary.

The present invention resides in combining, with the catch or keeper 3, novel means for 55 preventing disconnection between it and the pin 2 when the breastpin or brooch is positioned upon a garment.

In the form of embodiment of the invention shown in Figs. 1, 2, and 3 the attachment consists of a guard constructed, preferably, from resilient wire and bent to form an approximately U-shaped structure, the crest 5 of which is held combined with the body 1 by a perforated lug 6, soldered or brazed to 60 the body or to the plate or base 7 of the keeper. One member, 8, of the guard has its terminal provided with a hook 9, disposed at approximate right angles to the keeper 3 and is adapted to spring over the same, the other member, 70 10, of the guard being outturned to form a finger-hold 11, by which the hook 9 may be moved into and out of engagement with the beak of the keeper. As clearly shown in Fig. 3, the beak of the keeper does not project 75 through the hook 9, but partially enters the same, and the frictional contact between the hook and the beak will be sufficient to prevent any possibility of the accidental separation of the parts in use. This form of the invention is adapted for application to a pin or 80 brooch provided with the usual keeper, and to apply the same it will only be necessary to file or cut away a portion of the base of the keeper and then braze or otherwise secure the 85 lug 6 thereto.

In the form of embodiment of the invention shown in Fig. 4 the keeper and guard are exhibited as an article of manufacture to be applied to a pin or brooch in the usual manner. 90 This embodiment comprises a plate or base 12 of any preferred material, to which is secured the keeper 13 and guard 14, the latter being constructed on substantially the same lines as that shown in Figs. 1 to 3 and is held in cooperative relation with the keeper by a lug 15, which may be either brazed to the plate or base 12 or may form an integral part thereof by being struck up therefrom.

In the form of embodiment of the invention 100

shown in Fig. 5, which also is designed to be sold as an article of manufacture, the keeper 16 is of substantially the same construction as those shown in the other figures and is 5 brazed or otherwise combined with the plate or base 17; but the guard is somewhat differently formed and constitutes, in effect, a combined guard and stop, the latter additional function being provided in order to prevent 10 free movement of the pin within the keeper, such as is common with ordinary keepers. This is secured by extending the member 10 substantially across the keeper, as shown at 18, and curving the same, and the space be- 15 tween the upper side of the stop 18 thus formed and the under side of the keeper will be engaged by the pin, and it will thus be seen that the latter can only have a limited range of movement. The lug 19, in which 20 the combined guard and stop is held, may be either integral with the plate or base 17 or be struck up therefrom in the usual manner.

By making the guard of resilient metal when its hook is sprung over the beak of the 25 keeper it will be held positively positioned thereon, but may be readily thrown out of engagement therewith by exerting a backward pull upon the member or finger-hold 11.

While the devices as herein illustrated are 30 simple in construction, they will be found thoroughly efficient and durable in use and will in a ready and practical manner obviate certain objections inherent in devices of this character heretofore in use.

35 Having thus described the invention, what is claimed is:

1. The combination with a keeper, of a re-
silient guard having a member to interlock
with the beak of the keeper.

2. The combination with a keeper, of a re-
silient guard having at one end a hook to in-
terlock with the beak of the keeper, and at its
other end means whereby the guard may be
moved out of engagement with the keeper.

3. The combination with a keeper, of a guard
45 mounted for pivotal movement at right angles
to the face of the keeper and provided at one
end with a hook to straddle the beak of the
keeper, and at its other end with a finger-hold
50 projecting beyond the side of the keeper.

4. As a new article of manufacture, a com-
bined keeper and guard embodying a plate, a
keeper rigid therewith, and a guard mounted
55 for pivotal movement upon the plate and hav-
ing at one end a hook to straddle the beak of
the keeper, and at its other end a finger-hold.

5. As a new article of manufacture, a com-
bined keeper and guard comprising a plate, a
keeper rigid therewith, and a guard mounted
60 for pivotal movement upon the plate and hav-
ing one terminal formed into a hook to strad-
dle the beak of the keeper, and its other end
formed into a stop disposed transversely of
the keeper.

In testimony that I claim the foregoing as my
6 own I have hereto affixed my signature in the
presence of two witnesses.

ALVAH L. BENEDICT.
